United States Patent

Des. 236,674
Patented Sept. 9, 1975

236,674

TABLE

Evalin S. Gilbert, 2121 N. Bay Shore Drive,
Miami, Fla. 33137

Filed Nov. 20, 1972, Ser. No. 308,039

Term of patent 14 years

Int. Cl. D6—03

U.S. Cl. D6—177

FIG. 1

FIG. 2

FIG. 3

FIG. 1 is a view in side elevation of a table showing my design;

FIG. 2 is a top plan view; and

FIG. 3 is a view in end elevation thereof.

The side and end of the table not shown are like the side and end shown.

I claim:

The ornamental design for a table, substantially as shown and described.
